DEVICE FOR REMOVING PARTIAL DENTURES AND BRIDGES Carl F. Rasch, 1830 E. Romneya Drive,
Anaheim, Calif. 92805Filed Oct. 22, 1965, Ser. No. 501,944
1 Claim. (Cl. 32—40)**ABSTRACT OF THE DISCLOSURE**

A device for removing partial dentures is disclosed. This device is an elongated flat body of rectilinear cross-section having a hemispherical end. A notch is provided in the end so as to extend parallel to the sides of the body between the edges of the body. The device operates by engaging a wire, or clasp, of a partial denture in the notch and exerting a lifting force on the denture.

Human dental problems sometimes require the removal of one natural tooth or several adjacent natural teeth. Such removal results in difficulty of proper mastication, and when the removed natural teeth are at the front of the dental arch, the absence of such teeth is detrimental to the appearance. Accordingly, substitute devices have been designed therefor. These substitute devices resemble the removed teeth. However, in order to maintain the substitute devices in place, they must be secured to adjacent dental structure. Usually they are secured by embracing adjacent, natural teeth.

It is clear that such securing of the substitute devices must be rigid and strong so as to permit them to be fully used in mastication. Thus, firm, strong installation is desirable. However, natural teeth are not rigidly anchored, so that there is some relative movement therebetween during normal chewing processes. Furthermore, such substitute device must occasionally be removed for the cleaning thereof, and for the cleaning of the adjacent gum and tooth surfaces. Therefore, the structure which retains the substitute device in place must be resilient, yet removable. With such a resilient, firm grasp on the adjoining teeth, removability of such substitute device is often difficult.

Accordingly, it is an object of this invention to provide a device to aid in the removal of partial dentures and bridges, which device aids in such removal without damage to the partial dentures or bridges and without damage to the adjacent natural portions of the mouth.

It is a further object of this invention to provide a device for removing partial dentures and bridges which is of such shape that it can conveniently engage upon portions of a partial denture or bridge so as to grasp the partial denture or bridge for easy removal without distortion thereof and without undue engagement with the mouth.

It is a further object of this invention to provide a device for removing partial dentures and bridges which is economic to manufacture, provides a long trouble-free life and is easy to use so that the removal of such devices can readily be accomplished.

Other objects and advantages of this invention will become apparent from a study of the following portion of this specification, the claim and the attached drawings in which:

FIG. 1 is an isometric view of the device for removing partial dentures and bridges in accordance with this invention;

FIG. 2 is a top plan view thereof; and

FIG. 3 is a side elevational view thereof.

As an aid to understanding this invention it can be stated in essentially summary form that it is related to a

2

device for removing partial dentures and bridges. The device comprises an elongated bar having a substantially rectangular cross section. The widthwise dimension of the bar is substantially greater than the thickness thereof.

5 The operative end of the bar is completed with a hemicylindrical surface which joins tangent to the short edge walls. A slot is formed across the diameter of the hemicylindrical end, which slot opens on the hemicylindrical surface. The slot is sufficiently wide in the thickness direction of the bar to permit it to engage over clasps on partial dentures and bridges. The body of the bar is of sufficient size as to make it easily manually manipulatable, and in use the hemicylindrical end of the bar is placed in the mouth and the slot is used to engage over the clasp. Force in the direction for removal of the partial denture or bridge urges the clasp off of the adjacent tooth. Thus, the partial denture or bridge is removed. The same end of the device can be used for aid in inserting such a partial denture or bridge by engaging upon the clasp to force it into the inserted position. The material of the device is preferably of such hardness as to retain strength in the device, but still of insufficient hardness to cause scratching of the partial denture or bridge or scratching of the adjacent natural teeth.

10 This invention will be understood in greater detail by reference to the following portion of the specification wherein the drawings are described. Referring now specifically to the figures of the drawing, the device for removing partial dentures and bridges is indicated generally at 10. The device 10 has a manually operable body 12 and an operative end 14. The device 10 is of unitary construction and is of the same material throughout. The material is preferably such that the device 10 can be inexpensively manufactured. Accordingly, certain polymer composition materials suitable for injection molding are suitable for the device 10. The material should be rigid and tough enough in the finished device so as to permit the device 10 to hold its shape and not wear away at the edges. However, the material should be soft enough so that it is softer than the partial denture and bridges for which it is applicable and softer than natural teeth. Thus, the device 10 cannot scratch or damage the partial dentures, bridges or teeth.

15 The body 12 is preferably rectangular in section. It is relatively long, as seen in the left to right dimension in FIGS. 2 and 3. Furthermore, its sides 16 and 18 are considerably wider than its edges 20 and 22. While the body 12 is preferably rectangular in cross section, its edges need not be sharp but can be slightly rounded for comfortable manual engagement. End 24 can be of any convenient shape, such as the half octagon shown or can be hemicylindrical to match the operative end 14, if desired. Furthermore, end 24 can be identical to the operative end 14 should a double ended device 10 be preferred or desired.

20 Referring now to the operative end 14, the operative end is externally bounded by sides 16 and 18 and by hemicylindrical surfaces 26 and 28. The hemicylindrical surfaces 26 and 28 are formed about an axis at right angles to the sides 16 and 18. The hemicylindrical surfaces are tangent to the edges 20 and 22. Notch 30 is formed from the end of operative end 14 to the diameter of the hemicylindrical surfaces. Thus, hemicylinders are formed on the end of body 12 and comprise the operative end 14. Notch 30 is preferably approximately $\frac{1}{16}$ of an inch in dimension in a direction along the axis of the hemicylinder. This dimension is large enough to grasp the clasps upon partial dentures and bridges. Furthermore, the thickness of the hemicylinders, in a direction along their axis, is preferably such that each is approximately equal to the dimension of the notch 30.

Thus, this thickness of the hemicylinder is approximately $\frac{1}{16}$ of an inch.

Since the device 10 for removing partial dentures and bridges is a manual device, in use its body 12 is manually engaged. Such partial dentures and bridges comprise tooth simulating units which are positioned in a space where natural teeth have previously been removed. In order to maintain these tooth simulating units in place, clasps are provided thereon. These clasps comprise small resilient bands which are positioned to reach part way around the adjacent natural teeth and resiliently embrace them. When this resilient embrace is firm, the partial denture or bridge is difficult to remove. However, when the embrace is firm the partial denture or bridge is firmly placed, which is desirable during mastication. In use, the device 10 is positioned with its sides generally horizontal, or at right angles with respect to the teeth and the operative end 14 is positioned at one of the bands. The device 10 is positioned so that the band is engaged within a notch 30. Thereupon manual force, at right angles to the sides, urges the clasp with respect to the natural tooth. For an upper partial, downward force moves the clasp downward and thus moves the partial in the removal direction. The device 10 is alternatively inserted over the clasp at each end of the partial and thus removes the partial. It can be similarly used for the removal of lower partial dentures and bridges. It can similarly be used for the installation of partial dentures and bridges. After such are manually moved into place as far as is convenient, the device 10 can be engaged against the

clasp to move it into place. For such insertion, either end of the device 10 can be used.

This invention having been described in its preferred embodiment, it is clear that it is susceptible to numerous modifications and embodiments within the scope of this invention and without the exercise of the inventive faculty. Accordingly, the scope of this invention is defined by the scope of the following claim.

I claim:

1. A device for use in the removal of partial dentures which comprises: an elongated, flat body of a material which holds its shape, said body having a rectilinear cross section, said body having flat sides connected by edges, said body having a hemicylindrical end in which the curved surface of said end extends between said edges, said body having a notch in said hemicylindrical end, said notch extending from said hemicylindrical end between and parallel to said sides and having a bottom connecting said edges; and the bottom of said notch and the portions of said sides defining said notch each being about $\frac{1}{16}$ " thick.
